UNITED STATES PATENT OFFICE

ABRAHAM FRIEDMAN, OF LOS ANGELES, CALIFORNIA

DESIGN FOR A TABLE

Application filed December 15, 1930. Serial No. 37,994. Term of patent 7 years.

To all whom it may concern:

Be it known that I, ABRAHAM FRIEDMAN, a citizen of the United States, residing in the city and county of Los Angeles, State of California, have invented a new, original, and ornamental Design for a Table, of which the following is a specification, reference being had to the drawings on file in this application, forming a part thereof.

The figure is a perspective view of a table showing my new design.

I claim:

The ornamental design for a table as shown.

ABRAHAM FRIEDMAN.
